(57) **CLAIM**

The ornamental design for a paint edger with a replaceable applicator, as shown and described.

DESCRIPTION

FIG. 1 is a frontal perspective view of the paint edger with a replaceable applicator of the instant invention;

FIG. 2 is a front view thereof;

FIG. 3 is a back view thereof;

FIG. 4 is a left side view thereof;

FIG. 5 is a right side view thereof;

FIG. 6 is a top end view thereof;

FIG. 7 is a bottom end view thereof;

FIG. 8 is a back view of the replaceable applicator with extended attachment tabs;

FIG. 9 is an exploded back view of the replaceable applicator of FIG. 8 to be installed on a paint edger; and,

FIG. 10 is a back view illustrating the replaceable applicator of FIG. 8 secured to the paint edger.
